UNITED STATES PATENT OFFICE.

MARGARET M. ANDERSON, OF DETROIT, MICHIGAN.

PENCIL-STAMP.

1,108,314.

Specification of Letters Patent. Patented Aug. 25, 1914.

Application filed March 28, 1913. Serial No. 757,471.

To all whom it may concern:

Be it known that I, MARGARET M. ANDERSON, a citizen of the United States, residing at Detroit, in the county of Wayne and State 5 of Michigan, have invented a new and useful Pencil-Stamp, of which the following is a specification.

My invention relates to stamps, and more particularly to a stamp adapted to be attached to a pencil, penholder or the like.

The invention has among the objects thereof to provide a construction that is compact, that will add no appreciable weight to the pencil, penholder or the like, and 15 which may be easily and cheaply manufactured. Further, to provide a construction that while permitting the stamp to be used without materially changing the position of the pencil in the hand, will not hide the 20 point of the pencil or pen.

Other objects of the invention will more fully hereinafter appear.

The invention consists in the peculiar construction, arrangement and combination of 25 parts as hereinafter set forth and particularly pointed out in the claim.

In the drawings, Figure 1 is a side elevation showing my improvement as applied to a pencil; Fig. 2 is a sectional side elevation; 30 and Fig. 3 is a section on the line $x-x$ of Fig. 1.

A designates a pencil and B a stamp embodying the invention. The construction herein illustrated comprises a body portion 35 C, forming a means of attachment to the pencil, and a holder section D for the stamp proper E. The attaching section C, as shown, is formed of a longitudinally split sleeve of spring metal, so as to permit the 40 section C to be readily engaged with pencils or pens of various diameters, and when engaged, to remain in whatever position of longitudinal adjustment it is moved to. The holder D is formed of a U-shaped metallic strip having the top F soldered or otherwise suitably secured to the member C, as best shown in Fig. 2. This holder extends laterally from the member C and at an 45 angle thereof, so that when the pencil is in position for writing, the same will be arranged in proper relation to be pressed into engagement with the article to be printed.

However, the height of the holder D and the stamp E is such that by positioning these parts slightly in rear of the point, they 55 will not interfere with the operation of writing, but will be maintained a slight distance above the surface written upon. The member C is provided adjacent the lower end and on the bottom face thereof with 60 a downwardly-extending projection G stamped out of the bottom face of the member C so as to form a flat bearing surface H for engaging the top face I of the U-shaped stamp-holding section D. This arrangement permits the arranging of the 65 holder at the proper angle in relation to the member C.

The construction hereinbefore described is one that may be very easily manufactured, 70 will not—as before stated—interfere with the operation of writing, nor will it hide the pencil point from the operator. Also it is not necessary to turn the pencil over to affix the stamp, but it is merely necessary to 75 change the angle of the pencil to the surface to be stamped.

My improved construction is exceedingly desirable for libraries or the like, where it is necessary to not only stamp the card or other 80 article, but also to make a notation thereon with a pencil or pen. Furthermore, because of the simplicity and lightness of the device, it in no way makes the pen or pencil cumbersome.

While I have described the preferred 85 form of my invention, I do not wish to limit my protection to the exact construction shown.

What I claim as my invention is:—

An attachment for a pen or pencil, comprising a tubular sleeve having a longitudinal slot extending uninterruptedly from end to end, and a U-shaped stamp-holding section extending laterally of and beneath the 95 sleeve, said sleeve being provided with a downwardly-extending attaching section connected to the top of the stamp-holding section intermediate the ends of the latter.

MARGARET M. ANDERSON.
